UNITED STATES PATENT OFFICE.

WALTER W. WENHOLZ, OF ROCHESTER, NEW YORK, ASSIGNOR TO GENERAL RAILWAY SIGNAL COMPANY, OF ROCHESTER, NEW YORK.

ABSOLUTE-PERMISSIVE-BLOCK TRAIN-CONTROL SYSTEM.

Application filed March 14, 1925. Serial No. 15,504.

This invention relates to train control systems of the continuous inductive type, and more particularly to trackway apparatus for such systems for governing the movement of 5 trains in accordance with the signal restrictions imposed by wayside signals of the absolute permissive type.

In train control systems of the continuous inductive type in which occupied block protection is afforded by detecting by suitable car-carried apparatus the flow of current in the usual track circuit ahead of a train, it is necessary that current be applied across the rails at the exit end of a block or track 15 section for the particular direction in which the train is moving at a particular time; this being true for single track roads where trains run in both directions over the same track as well as in double track systems 20 where trains run in one direction only.

Train control systems of the general type mentioned may be said to be classified into two groups, namely, (1) the two-position type in which the train is governed solely 25 by the presence and absence respectively of current flowing in the usual track circuit flowing down one rail and back through the other, such as shown in the prior application of Wenholz, Serial No. 704,749, filed April 7, 1924; and (2) three-position systems in 30 which the train is governed in accordance with the presence and phase relation of two different currents flowing respectively in the usual track circuit ahead of the train and in a simplex circuit comprising the two rails in multiple, such as is shown in the application of Howe and Bushnell, Serial No. 653,898, filed July 26, 1923. Since the control of the currents applied to the exit end 35 of the block for both of these types or groups of systems is very much the same, the present application will for convenience be confined to a system of the two-position type.

In railway signaling systems of the absolute permissive type as ordinarily installed 40 each block consists of two insulated track sections in which the source of trackway energy is applied at the joining ends of these sections, and one specific feature of the 45 present invention resides in the provision of means for applying track circuit energy for train control purposes to the track rails on one side or the other of such intermediate point in a block when such train control cur-

rent is required of the train without the provision of additional line wires. 55

Other objects and purposes of the present invention reside in the provision of means for saving energy used for train control purposes by constructing the control apparatus 60 so that energy for train control purposes for one direction of movement is only applied when there is a train moving in that particular direction at some point between two passing sidings. 65

In describing the invention in detail reference will be made to the accompanying drawing in which:—

Fig. 1 illustrates many of the essential parts of the trackway apparatus from one 70 passing siding to another of an absolute permissive block signal system having train control trackway apparatus embodying the present invention superimposed thereon; 75 and

Fig. 2 shows in detail the circuit arrangement and apparatus for one complete block and the adjacent ends of two other blocks.

Referring to the drawings, an effort has been made to simplify the description of the 80 present invention by illustrating all of the west bound control apparatus and signals above the track and illustrating the east bound apparatus below the track, that is, illustrating the apparatus and signals which 85 govern a certain direction of movement on the right hand side of the track when facing in that direction, and also by applying reference characters to the various devices which speak for themselves. 90

Generally speaking, the block signal system as shown is of the type commonly known as an absolute permissive block system and is shown and described in detail in the prior patent to Wight, Serial Number 1,294,736, 95 February 18, 1919, so that for the purpose of explaining the present invention only a brief description of the system itself will be necessary.

The stretch of track between the two passing sidings PS¹ and PS² is divided in the usual way into a number of trackway sections, which have been designated A, B, C, etc. Each of these track sections is provided with the usual track battery shown, 100 and a track relay T having an exponent 105 corresponding to the section in which the track relay is located. Trains travel over

2

this stretch of single track in both directions, as indicated by the arrows M and N. Signals Z^1 , Z^3 , Z^5 and Z^7 govern the movement of traffic from east to west, whereas signals Z^2 , Z^4 , Z^6 and Z^8 govern the movement of traffic from west to east. These signals may be of any well known or suitable construction, but are shown as semaphore signals of the three-position type. The signals Z^2 and Z^7 govern the movement of trains in opposite directions into the single track section between the sidings, and are of the type called absolute or starting signals. These absolute signals are made distinguishable from the other intermediate permissive signals by having square ended blades, as shown, or by the arrangement of marker lights.

Adjacent each of these signals is a home relay. The home relays which govern west-bound signals have the reference characters HW applied thereto, and the home relays which govern east-bound signals have the reference characters HE applied thereto, and the exponents applied to each of these reference characters correspond to the number of the signal which this relay controls directly.

Each end of each of the track sections illustrated must at some time or other, depending on traffic conditions and the direction of movement of traffic, have alternating current impressed across the rails, and for this purpose transformers P have been illustrated. The transformer governing west-bound traffic having exponents "aw", "bw", etc., applied thereto and the transformer governing east-bound traffic have exponents "ae", "be", etc., applied thereto. These exponents correspond to the section in which the transformer is located and the direction of traffic it governs. The manner in which these transformers are energized is illustrated in Fig. 2 and more particularly described hereinafter. It should be noted that those transformers which are located at the battery end of a track section have their secondary windings connected in series with such batteries, and that the transformers connected at the relay end of a track section are connected in multiple across the relay but have a limiting resistance connected in series therewith. This limiting resistance is provided so that the secondary winding of the transformer does not effectively shunt, so to speak, the track relay of that section.

Referring particularly to Fig. 1, it should be noted that the home relay HW³ for the signal Z^3 is controlled by a line circuit (from which certain contacts have been omitted in Fig. 1 but have been shown in Fig. 2) including the front contact 10¹ of the home relay HW¹, front contact 11² of the track relay T^a, front contact 12³ of the track relay

T^b, so that this home relay HW³ is de-energized whenever home relay HW¹ is de-energized, this also being true of the home relays HW⁵ and HW⁷ with respect to the home relay next to the left. In the same way, the home relay HE⁶ is controlled by front contact 14⁶ of track relay T^c, front contact 15⁷ of track relay T^d and front contact 16⁸ of home relay HE⁸ so that the home relay HE⁶ is de-energized whenever the home relay HE⁸ is de-energized, the same thing being true of home relays HE⁴ and HE² with respect to corresponding home relays.

From the foregoing it will readily appear that, as far as the illustration in Fig. 1 of the drawings is concerned, a train entering the section of track from the passing siding PS¹ will cause all of the home relays HW⁶, HW⁴ and HW² to assume the de-energized position and will cause only the home relay HE² of the various east-bound home relays HE to be de-energized. It should be noted at this time, that the circuits for energizing the various home relays begin at either the positive or negative terminal of the battery as indicated by the reference character B ± (B plus or minus) and terminate at a common return wire C connected to the other side of such battery, so that, these three-position home relays may be energized to indicate normal and reverse depending on the polarity of the current applied thereto. Each of these home relays directly controls the signal adjacent to which it is located, and causes this signal to assume the clear position when the relay is energized to its normal position, causes the signal to assume the caution position when the relay assumes the dotted reversed position and causes it to assume the danger position when the corresponding home relay is de-energized. In other words, when an east-bound train enters a section between the passing sidings all of the west-bound signals will assume their danger position, whereas the east-bound signals will not change from the clear to danger position until the train passes such signal. In order to permit two trains to pass through the section one behind the other, and be properly protected by signal indications and train control, that is, in order to cause the signal of the first block in the rear of an occupied block to manifest caution conditions and the signals of all blocks in the rear thereof to indicate clear, it is necessary to provide supplemental means for picking up the east-bound home relays in the rear of such east-bound train; and for this purpose the line circuits heretofore traced are modified as more clearly shown in Fig. 2 of the drawings, this modification including a stick relay which is picked up as the train approaches the control point at which it is located and which relay is again dropped when the train has

passed entirely out of the block (comprising two track sections) governing this signal as more particularly explained hereinafter. These stick relays have been designated SE and SW, where E and W correspond to the direction of movement during which such relays are at times energized, and have an exponent applied thereto which corresponds to the signal adjacent to which such stick relay is located.

Referring now more particularly to Fig. 2 of the drawings in which the block comprising track section C and D, and the adjacent ends of two other track sections and associated apparatus has been illustrated, it should be noted that all of the signals are at clear and that each of the track transformers P shown are not connected to an alternating current source of supply, this, because one or the other of the pairs of contacts controlling the energizing circuits for these transformers is open.

The incomplete line circuit, shown in heavy lines in Fig. 1, for energizing the home relay HW³ heretofore traced in connection with home relay HW³ of Fig. 1 is completely shown in Fig. 2 in heavy lines and includes the following contacts:—contact 10³ having in multiple therewith a contact 13³ operated by the stick relay SW³, back contact 20⁴ of the stick relay SE⁴, and the contacts 11⁴ and 12⁴ of the track relays T⁴ and T⁴ respectively heretofore mentioned in connection with this circuit. Similar circuits may be traced for the other home relays.

Operation.—It is believed sufficient for a clear understanding of the system to consider the movement of a train through several blocks in one direction only, and note the changes in the relays and signals and when train control current is applied to and removed from the various track transformers, from which it is readily appreciated how other trains equipped for continuous inductive train control are restricted in their movement.

Let us assume that a train is moving from left to right in the section B. Under this condition the track relay T⁴ (see Fig. 2), is de-energized. This has no particular effect, because the relay HW³ was de-energized when the train was still in section A, so that the stick relay SW³ is not picked up. With the front contact 10³ of the home relay HW³ in its retracted position the west-bound home repeater relay or intermediate relay HRW and the home relay HW³ for reasons heretofore given, assume their retracted position. Dropping of the home relay HW³ also completes a circuit for energizing the transformer P^{3e} which circuit includes the front contact 21³ of the home relay HW³ and front contact 22⁴ of the home relay HE⁴ in series. Dropping of the west-bound repeater relay

HRW causes the completion of a circuit for energizing the transformer P^{3e} which circuit includes a back neutral contact 24¹ of this relay HRW, a polar contact 25¹ of the east-bound repeater polar neutral relay HRE, a 70 neutral contact 26 of the same relay in series. In a similar way energy is applied to the transformer P^{3e} through a back contact 21⁵ of west-bound home relay HW⁵ and a front contact 22⁶ of the east-bound home relay HE⁶ in series, and so on all the way through the single track section to the next passing siding. So that, each of the transformers illustrated in Fig. 2 which govern the movement of traffic from left to right is energized. 80

If now the train in question, moving from left to right, enters the track section C, the track relay T⁴ assumes its de-energized position and in turn de-energizes the home relay HE⁴. With the track relay T⁴ de-energized and the signal Z⁴, which by reason of de-energization of the home relay HE⁴, now moves to its danger position, and while moving from its clear to its caution position, completes a pick-up circuit for the stick relay SE⁴ through a circuit including the contact O⁴ controlled by the signal blade of signal Z⁴ and back contact 30⁴ of the track relay T⁴; so that, this stick relay SE⁴ assumes its energized position. With this relay SE⁴ once energized a stick circuit is completed which includes the back contact 31⁴ of the home relay HE⁴ and the front contact 32⁴ of the stick relay SE⁴, so that, this relay is stuck up so long as the home relay HE⁴ is in its retracted position. 100

Each of the signals also includes a pole changer switch PC which assumes the normal position illustrated during the clear and caution position of the signal, but assumes the dotted position when the corresponding signal is in the danger position, so that, the pole changer switch PC⁴ now assumes the dotted position since the signal Z⁴ assumes the danger position. With this pole changer switch PC⁴ reversed and the stick relay SE⁴ energized, negative energy is applied to the line wire (see Fig. 1) controlling the next home relay HE⁵ in the rear (and also the repeater relay connected to this line wire, not shown) through contact 17⁴ of the stick relay SE⁴, so that these relays are energized to the reverse position. With the home relay HE⁵ energized to the reverse position the signal Z⁵ assumes the caution position. 110

As the rear end of the train leaves the section B the track relay T⁴ again assumes its energized position thereby re-energizing the line relay HW⁴. Since the home relay HE⁴ is still de-energized current is incidentally applied to the track transformer P^{4e} as is obvious from Fig. 2 of the drawing. This application of current permitting west-bound movement while a train is moving eastward is harmless, because it oc- 120

4

5 curs only when the track section to which it is applied is occupied, so that, the current is shunted away and can not reach a west-bound train. It should however be borne 10 5 in mind that when there is another train following the train in question in the same single track stretch of trackway, the relay HW is not re-energized at this time.

10 As the train now passes from the section C into the section D the track relay T^a is de-energized causing its contacts to drop. The dropping of contact 12^a produces no effect because the line circuit in which it is contained is already open. Dropping of contact 15 ^{a} de-energizes the home repeater relay HRE connected to the other line wire, so that alternating current source of supply is cut off of the transformer P^{ce} so that the track section C is no longer provided with 20 alternating current and therefore does not permit unrestricted east-bound movement of a train in the rear of the train in question, and dropping of contact 35^a of the track relay T^a closes a break in the pick-up circuit for 25 the stick relay SW ^{a} , but this circuit can not be completed because the signal Z ^{a} has long previously assumed its danger position, so that the net result of passing into section D is the de-energization of the transformer P^{ce} . 30 Let us now assume that the train continues its movement in the east-bound direction and enters the track section E (see Fig. 2) as it enters this track section the stick relay SE ^{a} is picked up and stuck up in a 35 manner as heretofore described in connection with stick relay SE ^{a} , and the movement of the signal Z ^{a} to the danger position causes reversal of the pole changer switch PC ^{a} . As soon as the rear end of 40 the train leaves the section D, in addition to the fact that home relay HW ^{a} picks up if there is no other train following the train in question as heretofore mentioned, the track relay T^a again picks up; whereby 45 negative energy is applied to the line circuit including front contact 17^a of the stick relay SE ^{a} , back contact 37^a of the stick relay SW ^{a} , front contact 15^a of the track relay T^a , front contact 14^a of the track relay 50 T^a and the home relay HE ^{a} in series, so that this home relay HE ^{a} is energized to its reversed dotted position and causes the signal Z ^{a} to assume the caution position.

55 As soon as this occurs, on the assumption that there is another train in the single track section following the train in question, the transformer P^{be} is again energized, so that, a following train may detect alternating current in the track rails ahead of it and proceed unrestricted up to the transformer P^{be} . By reason of energization of the line wire just mentioned the east-bound home repeater relay HRE is also energized, but in this case it is energized by current of 60 reversed polarity, so that, the polarized con-

tact 25 thereof assumes the left hand position and does not yet re-apply current to the transformer P^{ce} .

As the train proceeds through the track section E and finally moves entirely out of this section, the track relay T^a again picks up, but this does not effect energization of the home relay HE ^{a} because the line circuit for this home relay is open at the front contact 15^a of the track relay T^a (see Fig. 1), but when this train has passed out of the section F the track relay T^a picks up and completes an energizing circuit for the home relay HE ^{a} , but the current applied to this relay HE ^{a} is of negative polarity for 70 reasons heretofore given, so that, the signal Z ^{a} assumes only its caution position, but this change in the signal Z ^{a} causes the pole changer switch PC ^{a} to again assume its normal position. With this pole changer 75 switch returned to normal by snap action, current of a positive polarity is re-applied to the line wire fed from this pole changer switch, and in turn the repeater home relay HRE is energized to the normal position; so that if another train is following the train in question and by so doing, de-energizes the repeater relay HRW, current is re-applied to the transformer P^{ce} so 80 as to permit unrestricted movement of such 85 following train up to this transformer P^{ce} at least. Also, the picking up of home relay HE ^{a} to the reverse position effects closing of contact 22^a and re-energization of the transformer P^{de} , so that, proceeding on the assumption that a train is approaching from 90 the rear, this train may detect current in the track rails and proceed unrestricted up the signal Z ^{a} . Also, upon further progress of 95 the train, positive energy is reapplied to the home relay HE ^{a} which causes the signal Z ^{a} to assume the normal clear position. 100

105 From the foregoing description of the invention it readily appears that the entrance of a train into a single track section causes the application of alternating current to all 110 of the transformers connected to the exit end of the various sections for the particular direction of movement in question. In this case it should be noted that the entrance of a 115 train into the first section is accompanied by the dropping of the track relay T^a or T^b , as the case may be, and effects the application of such alternating current to the transformer of the corresponding section. In practice, the time necessary to apply the alternating current to the transformer after this relay changes is less than that necessary to effect a speed restriction upon the train. 120 In other words, the train carried mechanism intended to be employed in connection with the trackway apparatus embodying the present invention, is such, that a train may travel for a predetermined period of time or 125 a predetermined distance without being 130

restricted even though no alternating current can be detected in the track rails at the time. Also, as a train passes through the single track section no trackway current can be detected by a train immediately in the rear of the train in question in the same track circuit, nor can such train detect current in the track circuit of the next block in the rear of a block occupied by a train, so that, the net result is restriction of movement of trains in the rear of the first train for at least one block (two sections) in addition to the block occupied by such train, and absolute restriction of movement of trains in the opposite direction to that of the train in question in all the blocks ahead of the train in a single track section.

By looking at Fig. 2 of the drawings it will be observed that only two line wires extend from the signals Z^3 and Z^4 to the signals Z^5 and Z^6 , and, as is understood by those skilled in the art of the single track signaling, these two line wires are employed in the usual absolute permissive block signaling systems, so that, no additional line wires are necessary in accordance with the present invention for applying trackway apparatus for train control, of the continuous inductive type, to an absolute permissive block signaling system of a well known and commercial type such as described in the patent heretofore mentioned. Also, in accordance with the present invention a great saving of energy is effected because no alternating current is necessary on any of the track transformers P shown except when a train is moving in a section between two passing sidings, and then, only the transformers for the direction of movement in which that particular train is moving are energized.

Having thus shown and described, rather specifically, one particular arrangement whereby train control of the continuous inductive type may be applied to single track signaling systems of the absolute permissive type, it is desired to be understood that this specific disclosure has been made to convey the operating features of a system embodying the present invention rather than illustrating the particular circuit arrangement preferably employed in practice, and that various changes, modification and additions may be made to adapt the invention to other types of single track signaling or train control systems. For instance, the same general method of energy saving accomplished by the approach control may be applied to slightly modified absolute-permissive-block signaling systems employing continuous inductive type train control; also a train control system requiring the presence of both simplex and track phase current in the trackway, commonly known as three-position system may be applied to the single

track signaling system shown, without departing from the scope of the invention or the idea of means underlying the same.

What it is desired to be secured by Letters Patent is:—

1. In combination, a stretch of railway track divided into blocks, each block comprising two sections divided by insulating joints, polar relays at the entrance end to each block for each direction of movement at all times assuming a position depending on traffic conditions both as to the presence and locations of a train and as to the direction in which such train is moving, and means including such polar relays for applying current to the track rails at the exit end of each section of the stretch of track when there is a train moving over such stretch in a certain direction except the section in the rear of such train of the block occupied by a train and the sections of the block in the rear of such train.

2. In combination, a stretch of railway track divided into blocks, each block comprising two sections divided by an insulated joint, a track relay and a source of direct current connected in series with each section arranged so that the direct current sources are located at intermediate points in the blocks, transformers having the secondary connected in series with said direct current sources of energy and in multiple with said track relays, line circuits connecting the ends of the blocks, an alternating current transmission line, relays located at the junctions of the sections of each block and controlled in accordance with traffic conditions as manifested by track relays in advance thereof through the medium of said line circuits, said relays having contacts for connecting the transmission lines to the transformers located at the exit end of a section when a train moves in such stretch of track in a particular direction.

3. In combination, a stretch of railway track divided into control zones, a polar relay at the entrance end to each zone for both directions of travel which assumes a position in accordance with traffic conditions by manifesting dangerous traffic conditions when there is a train in that zone or the next zone in advance traveling in the direction governed by that relay, or there is a train any distance in advance in such stretch traveling in the opposite direction, a line wire for each of said relays extending along the zone for governing such relays in accordance with traffic conditions ahead, means including said line wire for applying alternating current to the exit end of the first section of such zone when there is a train moving in that direction in said stretch of track but is not yet occupying the second section of the zone in question.

4. Trackway apparatus for automatic

train control systems of the continuous inductive type comprising in combination, a stretch of trackway divided into blocks each constituting two sections divided by an insulating joint; a polar relay at the entrance end to each block for each direction of travel manifesting danger when the block at the entrance to which it is located is occupied by a train moving in that direction or any block in the stretch of track in advance thereof is occupied by a train moving in the opposite direction, said relay indicating caution if the next block in advance is occupied by a train moving in the first mentioned direction and indicating clear if all the blocks in advance of such stretch of trackway are clear; a transformer at the exit end of each section for governing the movement of trains for a particular direction of travel; a line wire for each relay extending along the block at the entrance to which such relay is located; means for applying alternating current to the transformer at the exit end of the block when the polar relay at the entrance to the block next in advance indicates clear, and an intermediate relay for each line wire located at an intermediate point in the block for applying alternating current to the transformer at the exit end of the first section of a block when the polar relay at the entrance end to the next block in advance is indicating clear and the section in advance of such intermediate relay is unoccupied.

5. Trackway apparatus for automatic train control systems of the continuous inductive type comprising in combination, a stretch of track divided into blocks each constituting two sections divided by an insulated joint; a polar relay at the entrance end to each block for each direction of travel manifesting danger when the block at the entrance to which it is located is occupied by a train moving in that direction or any block in the stretch of track in advance thereof is occupied by a train moving in the opposite direction, said relay indicating caution if the next block in advance is occupied by a train moving in the first mentioned direction and indicating clear if all the blocks in advance of such stretch of trackway are clear; a transformer at the exit end of each section for governing the movement of a train for a corresponding direction of travel; a line wire for each polar relay extending along the block at the entrance to which such relay is located controlled by the polar relay of the block next in advance and the track relay of the second section of the block next in the rear; means governed by the polar relay at the entrance to one block for under clear traffic conditions of such block applying alternating current to the transformer at the exit end of the block in the rear thereof, a supplemental relay at the exit end of the first section of the block in the rear of said one block connected directly to one of the line wires and for applying alternating current to the transformer at the exit end of said first section when both said one block and the second section of the block in the rear thereof are unoccupied.

40 6. Trackway apparatus for automatic train control systems of the continuous inductive type comprising in combination, a stretch of track divided into blocks each constituting two sections divided by insulating joints of which each block is divided into two sections by insulating joints, a transformer for each section having its secondary winding connected across the rails at the exit end of such section, a track relay for each section, a line relay at the entrance end of each block, an energizing circuit for said line relay including a line wire extending throughout the length of such block and including a contact closed if the next block in advance is unoccupied and also including contacts of the track relays of the first and second section for normal direction of traffic, an intermediate relay located at the junction of two sections of a block connected in multiples with said line relay in a manner to be governed by the track relay of the second section of said block for the normal direc-

rent to the transformer at the exit end of said first section when said one block is unoccupied.

6. Trackway apparatus for automatic train control systems of the continuous inductive type comprising in combination, a stretch of trackway divided into blocks each constituting two sections divided by an insulating joint; a polar relay at the entrance end to each block for each direction of travel governed by track relays of the two sections of such block for manifesting danger when the block at the entrance to which a particular relay is located is occupied by a train moving in that direction or any block in the stretch of track in advance thereof is occupied by a train moving in the opposite direction, said polar relay indicating caution if the next block in advance of such block is occupied by a train moving in the first mentioned direction and indicating clear if all the blocks in advance in such stretch of trackway are clear; a transformer at the exit end of each section for governing the movement of a train for a corresponding direction of travel; a line wire for each polar relay extending along the block at the entrance to which such relay is located controlled by the polar relay of the block next in advance and the track relay of the second section of the block next in the rear; means governed by the polar relay at the entrance to one block for under clear traffic conditions of such block applying alternating current to the transformer at the exit end of the block in the rear thereof, a supplemental relay at the exit end of the first section of the block in the rear of said one block connected directly to one of the line wires and for applying alternating current to the transformer at the exit end of said first section when both said one block and the second section of the block in the rear thereof are unoccupied.

105 7. In an automatic train control system of the continuous inductive type, the combination with a track divided into blocks by insulating joints of which each block is divided into two sections by insulating joints, a transformer for each section having its secondary winding connected across the rails at the exit end of such section, a track relay for each section, a line relay at the entrance end of each block, an energizing circuit for said line relay including a line wire extending throughout the length of such block and including a contact closed if the next block in advance is unoccupied and also including contacts of the track relays of the first and second section for normal direction of traffic, an intermediate relay located at the junction of two sections of a block connected in multiples with said line relay in a manner to be governed by the track relay of the second section of said block for the normal direc-

tion of traffic but not to be governed by the track relay of the first section, means for applying alternating current to the transformer of the last section of a block when the line relay at the entrance to the next block in advance is energized, and means for applying alternating current to the transformer of the first section when the intermediate relay at the exit end of such first section is energized.

8. In trackway apparatus for automatic train control system of the continuous inductive type, the combination with a track divided into blocks by insulating joints of which each block is divided into sections by insulating joints, a transformer for each section having its secondary winding connected across the rails at the exit end of such section, a track relay for each section, a line relay at the entrance end of each block, an energizing circuit for said relay including a line wire extending through the length of said block containing a contact closed if the next block in advance is unoccupied and including a contact of the track relay of each section, an intermediate relay located at a junction of two sections of a block connected in multiple with said line relay in a manner to be governed by the track relays of the sections of said block in advance of such junction for the normal direction of traffic but not governed by the track relays of the sections in the rear of such junction, means for applying alternating current to the transformer of the last section of a block when the line relay at the entrance end to the next block in advance is energized, and means for applying alternating current to the transformer of the section of the block in the rear of such junction when the intermediate relay at such junction is energized.

9. Trackway apparatus for automatic train control systems of the continuous inductive type comprising in combination, a stretch of track divided into blocks each constituting two sections divided by an insulated joint; a polar relay at the entrance end to each block for each direction of travel manifesting danger when the block at the entrance to which it is located is occupied by a train moving in that direction or any block in the stretch of track in advance thereof is occupied by a train moving in the opposite direction, said relay indicating caution if the next block in advance is occupied by a train moving in the first mentioned direction and indicating clear of two blocks in advance of such relay are unoccupied and the rest of the blocks in advance in said stretch are not occupied by a train moving in the opposite direction; a transformer at the exit end of each section for governing the movement of trains for a particular direction of travel; a line wire for each polar relay extending along the block at the entrance to which such

polar relay is located; means governed by the polar relay at the entrance to one block for under clear traffic conditions of such block applying alternating current to the transformer at the exit end of the second section of the block in the rear thereof, and a supplemental relay at the exit end of the first section of the block in the rear of said one block connected directly to one of the line wires and controlled to apply alternating current to the transformer at the exit end of said first section when said one block and said second section are unoccupied.

10. Trackway apparatus for automatic train control systems of the continuous inductive type comprising in combination, a stretch of trackway divided into blocks each constituting two sections divided by an insulating joint; a polar relay at the entrance end of each block for each direction of travel governed by track relays of the two sections of such block for manifesting danger when the block at the entrance to which a particular relay is located is occupied by a train moving in that direction or any block in the stretch of track in advance thereof is occupied by a train moving in the opposite direction, said polar relay indicating caution if the next block in advance of such block is occupied by a train moving in the first mentioned direction and indicating clear if that block and the next block in advance in such stretch of trackway are clear and there is no train in advance moving in said opposite direction; a transformer at the exit end of each section for governing the movement of a train for a corresponding direction of travel; a line wire for each polar relay extending along the block at the entrance to which such relay is located controlled by the polar relay of the block next in advance and the track relays of the sections of the block in question; means governed by the polar relay at the entrance to one block for under clear traffic conditions of such block applying alternating current to the transformer at the exit end of the block in the rear thereof, and a supplemental relay at the exit end of the first section of the block in the rear of said one block connected directly to one of the line wires and governed to apply alternating current to the transformer at the exit end of said first section when both said one block and the second section of the block in the rear thereof are unoccupied.

11. Trackway apparatus for automatic train control systems of the continuous inductive type for single track railroads of the absolute-permissive-block type comprising; a stretch of single track divided into blocks by insulating joints of which each block is divided into two sections by insulating joints; a track circuit for each section including a source of current and a

- track relay; a transformer at the exit end of each section having its secondary winding connected in series with such source of energy or in multiple with such track relay as the case may be; an intermediate relay located at the junction of two sections of a block; a home relay at the entrance end to each block; a circuit for each intermediate relay including a source of energy, a front 10 contact of the home relay at the entrance to the block in advance and a front contact of the track relay of the section immediately ahead of said intermediate relay; a circuit for each home relay energized by the potential drop across the intermediate relay in advance and including a front contact of the track relay of the section between such home relay and such intermediate relay; a circuit for energizing the transformer at the exit 15 end of the second section of a block including a front contact of the home relay at the entrance to the block next in advance; and a circuit for energizing the transformer at the exit end of the first section of a block 20 including a front contact of the intermediate relay.
12. Trackway apparatus for automatic train control systems of the continuous inductive type for single track railroads of 30 the absolute-permissive-block type comprising; a stretch of single track divided into blocks by insulating joints of which each block is divided into two sections by insulating joints; a track circuit for each section 35 including a source of current and a track re-
- lay; a transformer for each end of each section having its secondary winding connected in series with such source of current or in multiple with such track relay as the case may be; an intermediate relay located at the 40 junction of two sections of a block for each direction of movement; a home relay at the entrance end to each block for each direction of movement; a circuit for each intermediate relay including a source of energy, a front 45 contact of the home relay at the entrance to the block in advance and a front contact of the track relay of the section immediately ahead of said intermediate relay; a circuit for each home relay energized by the potential drop across the intermediate relay in advance and including a front contact of the track relay of the section between such home relay and such intermediate relay; a circuit for energizing the transformer 50 at the exit end of the second section of a block including a front contact of the home relay at the entrance to the next block in advance, and a back contact of the home relay at the exit end of the block in question; 55 and a circuit for energizing the transformer at the exit end of a first section of a block including a front contact of the intermediate relay of such block governing traffic in the corresponding direction and the back 60 contact of the intermediate relay of such block governing traffic in an opposite direction.

In testimony whereof I affix my signature.
WALTER W. WENHOLZ.
